The ornamental design for pants, as shown and described.

DESCRIPTION

FIG. 1 is a rear view of pants showing our new design;
 FIG. 2 is a left side view thereof, the right side view being a mirror image;
 FIG. 3 is a top plan view thereof;
 FIG. 4 is a bottom view thereof;
 FIG. 5 is a partial view thereof taken at portion **5-5** in FIG. 1;
 FIG. 6 is a cross-sectional view thereof taken along line **6-6** in FIG. 5; and,
 FIG. 7 is a front view thereof.
 The dot-dash broken lines shown on the drawings illustrate portions of the pants, and the dotted broken lines represent stitching; the broken lines form no part of the claimed design. The crosshatch marks represent a fabric material and are not a surface decoration.
